UNITED STATES PATENT OFFICE.

GEORGE PAUL HORAN, OF RUTLAND, VERMONT.

TRAIN-STOP MECHANISM.

Application filed July 8, 1921. Serial No. 483,236.

To all whom it may concern:

Be it known that I, GEORGE P. HORAN, a citizen of the United States, and a resident of Rutland, in the county of Rutland and State of Vermont, have invented a new and Improved Train-Stop Mechanism, of which the following is a full, clear, and exact description.

This invention relates to improvements in train stop mechanisms, and more particularly to an improved guard for the valve or cock of the train air line, an object of the invention being to provide means which prevents the operation of the valve by contact with snow, which protects the valve from stones or other objects on the track, but which permits the operation of the valve when the plunger designed to operate the same is in position.

20 A further object is to provide train stop mechanism which is shielded from accidental operation, but which assures operation at the proper time to prevent accident.

A further object is to provide improved mechanism which is designed for use in connection with mechanisms such as set forth in my co-pending application Serial No. 443,640 filed February 9, 1921, for train stop, although it is, of course, to be understood that the invention may be used in connection with any plunger or projection which is moved into position to open the air line and stop the train if any attempt is made to pass a danger signal.

35 With these and other objects in view the invention consists in certain novel features of construction, and combinations and arrangements of parts, as will be more fully hereinafter described and pointed out in the claims.

In the accompanying drawings—

Figure 1 is a fragmentary view in side elevation illustrating my improved guard in position for protecting the valve or cock of the air line.

Figure 2 is a view in section on the line 2—2 of Figure 1.

Figure 3 is a front elevation or end view of Figure 1.

50 Figure 4 is a view in transverse section on the line 4—4 of Figure 2.

Figures 5, 6 and 7 are views in plan, front elevation and side elevation respectively illustrating a fender which may be used in connection with my improved guard.

1 represents a track and 2 a plunger or

other form of abutment, which is movable into elevated, operative position and lowered out of operative position through any suitable mechanism, but preferably in connection with the signal as set forth in my pending application above referred to, although, of course, it is to be understood that this invention is not limited to any particular form of plunger or means to operate the same, it being understood that the invention will operate in connection with any form of plunger which is moved into position to be engaged by the arms 3 of a cock or valve 4 constituting an outlet for the air line 5 of a locomotive or car 6.

I have illustrated the forward portion of a locomotive as a conventional form of vehicle, but provide at the center of the pilot 7 an opening 8 for the passage of the plunger 2; in other words, to accommodate the plunger when the latter is in its operative position and the locomotive is moved forwardly over the same and in position to engage the arms 3 of the valve 4.

At opposite sides of the cock or valve 4 my improved guards 9 are located. These guards 9 are preferably of the shape shown; that is to say, that they are curved longitudinally in the arc of a circle or they may be otherwise shaped to provide cam surfaces and are preferably provided with outwardly or laterally projecting flanges or wings 10 located preferably at an angle of substantially forty-five degrees so as to function as cam surfaces when in contact with snow to hold the guards inwardly and in operative position. The inner faces of the guards are given a general compound curvature, as shown most clearly in Figure 2, so that the valve or cock 4 lies in a pocket or space with the operating arms 3 of the valve protected and shielded from contact with snow so as to prevent the accidental opening of the air line.

The guards 9, 9 are secured to and supported by bracket arms 11 preferably arranged in pairs and forming yokes, as shown in Figure 2, these arms being pivotally connected at their inner ends, as shown at 12, and at their outer ends being pivotally connected, as shown at 13, to supporting brackets 14, the latter fixed to any suitable part of the locomotive or vehicle and operating as hands from which the guards are suspended.

It will thus be noted that the guards hang

in such a position as to prevent a stone or other object from operating the air valve, as such object will first come in contact with one or the other, or both of the guards and be deflected. When the train is travelling through deep snow, the cam action of the snow against the outer or cam faces of the flanges or wings 10 will serve to hold the guards in their inward position and prevent them from being flared outwardly.

When, however, the plunger 2 is in elevated operative position, it will by reason of the curved or cam shape of the guards 9, enter between said guards and force them apart sufficiently to permit contact with the arms 3 of the valve 4 and open the air line as will be readily understood, the guards returning by gravity to their former position after the plunger is passed.

20 To protect the guards in case of heavy snow, from any possibility of movement, I may employ a rotary fender 14, such as shown in Figures 5, 6 and 7. This fender may comprise three or more blades or vanes 25 and have rotary mounting, such as shown at 15, in the opening or entrance 8 in the pilot 7. The blades or vanes of the fender 14 will cause a groove to be made in the deep snow through which the guards 9 will ride, but 30 when the plunger 2 is in elevated position, it will operate to turn or partially turn the fender 14 without injury either to the fender or the plunger. In other words, the fender will function to clear a path or knock 35 obstructions aside to prevent injury to the guards, but will not injure the operating plunger 2, as said fender will revolve or partially revolve when the plunger is in elevated position.

40 It will be noted that the air line valve 4 of the guards 9, as well as the fender 14, are in a plane above the plane of the lower edge of the pilot, hence, any large objects 45 on the track will be deflected by the pilot; smaller objects will be cared for by the fender and the guards, and even though the track will be piled with snow, this contingency is also compensated for by the arrangement of fender and the shape 50 of the guards, so that a proper operation of the air line is insured in the event the engine attempts to pass the plunger, which is, as above stated, preferably operated in connection with the danger signal.

55 Various slight changes might be made in the general form and arrangement of the parts described without departing from the invention and hence I do not limit myself to the precise details set forth, but consider 60 myself at liberty to make such changes and alterations as fairly fall within the spirit and scope of the appended claims.

I claim:

1. The combination with a vehicle having 65 a brake air line, a valve outlet for said

air line, and an arm on said valve adapted to be operated by a fixed member when passing the same, of a pair of guards pivotally supported and located at opposite sides of the valve and movable away from each other to admit the valve arm engaging member.

2. The combination with a vehicle having a brake air line, a valve outlet for said air line, and an arm on said valve adapted to be operated by a fixed member when passing 75 the same, of a pair of guards pivotally supported and located at opposite sides of the valve and movable away from each other to admit the valve arm engaging member, said guards having longitudinal and transverse 80 cam faces.

3. The combination with a vehicle having a brake air line, a valve outlet for said air line, and an arm on said valve adapted to be operated by a fixed member when passing the same, of a pair of guards pivotally supported and located at opposite sides of the valve and movable away from each other to admit the valve arm engaging member, said guards curve downwardly from both 90 ends toward their centers, and laterally projecting angularly disposed flanges on the outer faces of said guards.

4. The combination with a locomotive, and a pilot, said pilot having an entrance at its center and forward portion whereby the pilot may pass a valve operating member which is movable through said entrance, of an air valve supported by the locomotive and located in line with said entrance, arms 100 on said valve adapted to be engaged by the said member when the latter is in elevated position, hangers depending from the locomotive, and pivoted guards supported on the hangers and located at opposite sides of the 105 valve.

5. The combination with a locomotive, and a pilot, said pilot having an entrance at its center and forward portion whereby the pilot may pass a valve operating member which 110 is movable through said entrance, of an air valve supported by the locomotive and located in line with said entrance, arms on said valve adapted to be engaged by the said member when the latter is in elevated position, hangers depending from the locomotive, pivoted guards supported on the hangers and located at opposite sides of the valve, and bracket arms secured to the 115 guards pivotally connected at their inner ends and pivotally connected at their outer ends to said hangers.

6. The combination with a locomotive, and a pilot, said pilot having an entrance at its center and forward portion whereby the pilot may pass a valve operating member which is movable through said entrance, of an air valve supported by the locomotive and located in line with said entrance, arms 125 on said valve adapted to be engaged by the 130

said member when the latter is in elevated position, hangers depending from the locomotive, pivoted guards supported on the hangers and located at opposite sides of the 5 valve, and a rotary fender in said entrance in the pilot.

7. The combination with a locomotive, and a pilot, said pilot having an entrance at its center and forward portion whereby the 10 pilot may pass a valve operating member which is movable through said entrance, of

an air valve supported by the locomotive and located in line with said entrance, arms on said valve adapted to be engaged by the said member when the latter is in elevated position, hangers depending from the locomotive, pivoted guards supported on the hangers and located at opposite sides of the valve, and a rotary fender in said entrance in the pilot, said fender comprising a circular series 15 of blades or vanes.

GEORGE PAUL HORAN.
